Primary Examiner — Kevin K Rudzinski*Assistant Examiner* — Clare Ann Gannon(74) *Attorney, Agent, or Firm* — Malloy & Malloy, PL**CLAIM**

The ornamental design for a roller shade cassette cover, as shown and described.

DESCRIPTION

FIG. 1 is a front perspective view illustrating my design for a roller shade cassette cover;

FIG. 2 is a front perspective view thereof;

FIG. 3 is a right side view thereof;

FIG. 4 is a left side view thereof;

FIG. 5 is a top view thereof;

FIG. 6 is a top perspective view thereof;

FIG. 7 is a rear view thereof;

FIG. 8 is a rear perspective view thereof;

FIG. 9 is a bottom view thereof; and,

FIG. 10 is a bottom perspective view thereof.

The broken lines in the drawings depict boundaries and environmental structure that form no part of the design to be patented.
